LONG STROKE PUMP JACK

Luther A. Blackburn, Altadena, Calif., assignor of
one-half to Bernhard H. Scott, Glendale,
Calif.

Application October 21, 1939, Serial No. 300,606

9 Claims. (Cl. 74—37)

This invention relates to long stroke pumps, and the invention is particularly applicable in the construction of deep-well pumps. Deep-well pumps that involve the use of a reciprocating sucker rod or pump-rod actuated at the ground level are very inefficient due to the lengthening of the rod on the up-stroke which, of course, reduces the effective stroke.

The usual means for reciprocating the rod of a deep-well pump is the well-known walking beam, but practical considerations make it substantially impossible to obtain with it a stroke of more than four or five feet.

The present improvement involves the use of endless driving chains that operate to reciprocate a cross-head that is connected to the pump-rod. I am aware that chain drives have been suggested heretofore for this purpose, but they have not come into general use. This is probably due to the fact that they have not provided for properly counterbalancing the weight of the pump-rod. This involves considerable difficulties because of the fact that on the up-stroke the load on the driving chains includes the pump-rod and also the long column of oil surrounding the pump-rod above the standing valve which, of course, is open on the up-stroke.

An object of the present invention is to overcome these difficulties and to provide a chain drive capable of being constructed so as to enable a relatively long stroke for the pump-rod to be attained and at the same time provide for substantially perfect balancing of the load so that all of the forces acting on the cross head are substantially balanced with reference to the axis of the rod and also in such a way that substantially the same load is placed on the driving chains on the down stroke as well as on the up stroke. In this way the chains operate on a substantially constant load with the stresses always acting in the same direction in the chains.

A further object of the invention is to provide simple means for effecting constant lubrication of the chains.

A further object of the invention is to provide means for adjusting the bearings of the sprocket wheels supporting the chains to take up wear on the chains, and to accomplish this without interfering with the constant lubrication of the chains.

A further object of the invention is to provide adjusting means for the upper ends of the driving chains so constructed that it will provide means for imparting the entire load from the bearing blocks of the sprocket chains, to the

frame of the pump, at the same time providing simple means for effecting their vertical adjustment when the same becomes necessary.

In its construction the apparatus includes oppositely disposed drive chains located on opposite sides of the path of the cross head that is attached to the pump rod. In order to drive the pump rod, blocks are employed sliding in a transverse slot in the cross head. One of the objects of the invention is to improve the action in a construction of this kind to permit relative movement of the links that are connected to these blocks. This enables the chains to pass over the sprocket wheels without any danger of subjecting the connecting pin to any torsional strains.

A further object of the invention is to provide simple means for preventing whipping of the chains where the chains must be unusually long to provide for an extremely long stroke in the pump.

A further object of the invention is to provide means for facilitating the removal and replacement of the cross head from the cross head guide.

Further objects of the invention will appear hereinafter.

The invention consists in the novel parts and combination of parts to be described hereinafter, all of which contribute to produce an efficient long stroke pump jack.

A preferred embodiment of the invention is described in the following specification, while the broad scope of the invention is pointed out in the appended claims.

In the drawings:

Fig. 1 is a side elevation of a pumping apparatus embodying my invention, a portion of the cross head being broken away and shown partially in section. Also portions of the chains are broken away so as to display the cross head and contiguous parts.

Fig. 2 is also an elevation showing the side of the apparatus, illustrated in Fig. 1. In this view certain parts are broken away and at the bottom of the figure the lubricating bath is illustrated in section, as also the cross head that is attached to the pump rod. In this view the upper end of the flow pipe is omitted and the pump rod is shown broken away.

Fig. 2a is a side elevation showing the lower end of the hanger bar such as I employ for suspending and effecting the upward adjustment of the bearing blocks for the upper sprocket wheels.

Fig. 3 is a perspective of one of the blocks

which I prefer to employ for imparting movement from the chains to the pump cross head.

Fig. 4 is a vertical section showing a length of flow pipe and pump rod.

Fig. 5 is a vertical cross-section taken about on the line 5—5 of Fig. 1 upon an enlarged scale, and particularly illustrating the preferred details of the construction for connecting the driving pins or blocks that drive the cross heads, that is to say, for connecting the blocks to the opposed runs of the chains that drive the same.

Fig. 6 is a vertical section taken about on the line 6—6 of Fig. 1 upon an enlarged scale, and particularly illustrating the means for adjustably supporting the upper ends of the driving chains, that is to say, for supporting the bearing blocks for the sprocket wheels.

Fig. 7 is a horizontal section taken about on the line 7—7 of Fig. 1, and particularly illustrating the arrangement of the driving chains with reference to the cross head.

Fig. 8 is a horizontal section taken about the location of the line 8—8 of Fig. 1, upon an enlarged scale, certain parts being broken away. This view particularly illustrates the means for driving the lower sprocket wheels that carry the driving chains.

Before proceeding to a more detailed description of the invention, it should be stated that in its preferred embodiment I provide for counter-balancing the cross head that is attached to the pump rod in such a way that the forces acting on the rod are always balanced with reference to the axis of the rod.

Also in the preferred embodiment of the invention I provide four endless driving chains disposed in opposite pairs so that the cross head of the pump lies between the pairs of driving chains, and in such a way that two driving blocks or pins attached to the chains are arranged to engage the transverse slot of the cross head. The direction of movement of the chains is such that on the upstroke these blocks are located near the pump rod and on the down stroke they are remote from the pump rod. At all times, however, these two blocks are equi-distant from the axis of the rod so that the forces exerted by them on the cross head are perfectly balanced.

Although it is not essential to the invention to provide two separate counterweights, nevertheless I prefer to counterweight the pump rod in that way and these counterweights are located so that any strains developed by their presence are balanced. This tends to prevent the development of vibrations at the top of the frame, where the construction is of vertical type, disposed in such a way as to connect directly to the pump rod.

The driving chains referred to above, at their upper ends pass over sprocket wheels and likewise at their lower ends, and at these points the driving blocks referred to above move apart or approach each other. These blocks are attached to special links of opposed runs of the chains. I provide a special construction for this connection that will permit relative swiveling movement of these special links with reference to each other, thereby improving the construction.

The ends of the crosshead are guided by means of crosshead guides, and in order to facilitate the removal and replacement of the crosshead in the guides I provide a special construction for the guide that will permit this.

The bearing blocks that support the sprocket wheels at the ends of the chains, which of course support the entire load on the chains, are so constructed that while the pump is in operation an effective clamping of these bearing blocks is attained on the frame, enabling the entire weight of the load to be imparted immediately from the bearing blocks to the frame. At the same time the construction includes means for effecting an upward adjustment of the bearing blocks when the pump is not in operation.

Referring more particularly to the parts, and especially the Figs. 1 and 2, I provide a frame 1 that is preferably upright and located directly over the flow pipe 2, and the pump rod 3 that extends up from the flow pipe, and which is reciprocated to pump the well. This frame 1 may be of any suitable construction, but is preferably made up of structural shapes such as angle iron. In order to form a guide for the cross head 4 that actuates the pump rod, I prefer to provide two angle irons 5 connected together back to back (see Fig. 8) forming a T-iron guide with superposed flanges 6 that can be engaged by the ends of the cross head 4 in some manner such as indicated in Fig. 7. The cross head is constructed with a deep transverse slot 8 (see Fig. 1). The pump rod 3 passes up from below across this slot and is secured to the cross head by means of a clamp 9 that is of the usual construction, including bolts, that can be released to enable the cross head to be adjusted to any desired position on the pump rod, or vice versa. This clamp fits closely into openings 10 formed in webs 11 projecting up from the upper side of the cross head so that there is substantially no play in transmitting movement to the rod from the cross head.

The chain drive for the cross head preferably comprises four endless chains 12. These chains are disposed in pairs as illustrated in Figs. 7 and 8. As shown, the chains of each pair are located respectively on opposite sides of the plane of movement of the cross head. Corresponding runs of these pairs of chains are connected together by a connection 13 (see Fig. 5) which connects the runs at the slot 8 of the cross head so as to drive the cross head up and down. This connection 13 could consist of a mere pin, but I prefer to construct it so that it includes a block 14 having an opening or bore 15 through the same for a driving pin to pass through. Furthermore, the driving pin is preferably not constructed as a simple pin, but is so constructed as to give a certain amount of flexibility in the connection. This is desirable when the chain passes over the sprocket wheels at the upper and lower ends of the chains, as will be described hereinafter. Referring to Fig. 5, I prefer to provide two special links 16 in the chains, and these links 16 are connected together by a swivel pin connection, preferably comprising a solid pin 17 secured to one of the links 16, which is received in the sleeve or hollow pin 18 attached to the opposite link. In addition to this swiveling movement, it is also preferable to construct this connection so as to permit the chains to move slightly apart or toward each other. This enables them to adjust themselves to the planes of rotation of the sprocket wheels without any danger of straining the connection. For this purpose I prefer to form the solid pin 17 with a reduced neck 19 which receives the tip of a set-screw 20 screwed in through the side of the sleeve or tubular pin 18.

In the operation of the pump, the inside runs 21 of the chains move upwardly, so that the blocks 14 on the up stroke are located near the middle of the cross head. In this way these lifting forces are brought nearer to the location of the pump rod which of course is at the middle of the cross head.

Although the blocks 14 may have plain rubbing faces on their upper and lower sides, I prefer to provide anti-friction devices such as rollers 22 in their faces (see Fig. 3). The inner ends of the blocks are preferably provided with vertical clearance grooves 23 that provide clearance for the pump rod that lies between these blocks on the up stroke.

In practising the invention I counterweight the cross head and the load carried by it in such a way that the force exerted by the counterweight is applied in such a way that a perfect balance results. In other words, if a single counterweight were employed, the cable supporting it would be attached at the middle of the cross head and extend upwardly over a pulley at an elevated point above the frame, but not supported on the frame. That would achieve perfect balance. However, I prefer to provide counterweighting means carried on the frame 1, and in this instance I prefer to provide two oppositely disposed counterweights 24 (see Fig. 1) supported on lines or cables 25 that pass upwardly from the counterweights and over sheaves or pulleys 26, the inner ends of the cables passing downwardly and being attached to cross-pins 27 on the cross head (see Fig. 7). I prefer to provide two of these cables 25 on each side (see Fig. 2).

Each counterweight 24 preferably consists of a plurality of weights stacked together and tied together with a tie-bolt 28 that passes through all of them. This tie-bolt should fit snugly in the holes in the weights and should be clamped tight by nuts 29 on the upper ends of the tie bolts. This prevents any possibility of the individual weights shifting out of line.

As the cables 25 are attached substantially at the middle of the cross-head on each side of the sucker rod, they exert a direct pull on the cross-head in perfect balance.

The counterweights are guided on the corner angle irons 30 in the manner indicated in Fig. 7, slide bolts 31 being provided between the inner edges of the angle irons with keeper plates 32 bolted on each side of the flanges. This arrangement insures the proper guiding of these counterweights and prevents any lateral movement in them as they move up and down.

In order to maintain a constant load on the driving chains, that is to say, an unvarying load, these counterweights 24 have a weight that is substantially three-quarters of the total load on the cross head on the up stroke. For example, suppose that in a 6,000-foot well the weight of the pump rod is 9,000 pounds. In that case I would construct the pump so that the weight of the column of liquid being pumped is substantially equal to the weight of an equal length of the pump rod. In this connection reference is had to Fig. 4 illustrating a length of flow pipe and pump rod. In order to determine the proper relative diameters of the rod and flow pipe, it is merely necessary to proportion them so that the area of the rod multiplied by its specific gravity is equal to the area of the column of liquid multiplied by its specific gravity. The result of this would be that, assuming that the pump rod 75

weighed 9000 pounds, then the total load on the up stroke would be 18,000 pounds. In that case the counterweights should have a total weight of 13,500 pounds. This gives a net load on the down stroke of 4500 pounds and a net load on the up stroke of 450 pounds. This enables the motor driving the chains to operate at a substantially constant load, and it is merely necessary to provide a fly-wheel or fly-wheels to assist in overcoming the inertia of the counterweights at the lower end of their travel.

The driving chains are preferably driven at the base of the apparatus. If desired they may be driven from a motor at the side of the well through the agency of a belt, but in the present instance I illustrate a motor 33 which may be of any type, for example, a gas-engine or an electric motor, and this motor through a belt 34 drives a horizontal countershaft 35 (see Figs. 1 and 8). This countershaft extends across the frame, being supported by suitable bearings 36 and is provided with pinions 37 for driving the lower sprocket wheels 38 over which the sprocket chains run. In order to accomplish this in a simple manner and to drive the chains in the proper directions, the shafts 39 of the sprocket wheels 38 are provided with gear wheels 40 of equal diameter and meshing together. One of these wheels meshes on its outer side with the sprocket wheel 37. By reason of the fact that the chains are driven at the base of the frame, of course the vibration of the frame is greatly reduced. This greatly reduces any tendency of the runs of the chains to "whip," which there is a tendency to do, particularly in a pump construction having an unusually long stroke.

However, in order to prevent any whipping tendencies in the chains, I prefer to provide means for engaging them at intermediate points on their lengths, and for this purpose I prefer to provide idle sprocket wheels 41 (see Fig. 1) corresponding to each chain 12 and disposed between the runs of the chains. These idle sprockets are mounted in suitable bearings supported on horizontal frame members 42. If desired, these sprocket wheels may be made slightly oversize so that they will not only prevent the runs of the chains from swinging toward each other, but will also guide the chains slightly out of line so that they will not have any tendency to move further away from each other.

In order to maintain the chains and all parts working adjacent to them lubricated, I prefer to provide a lubricating bath or oil bath 43 (see Fig. 2) in which the lower ends of the chains dip. I prefer to provide a common oil bath for all four chains and permit the pump rod 3 to pass up through it. In order to accomplish this it is necessary to provide a sleeve or tubular housing 44 that extends up from the bottom of the oil tank to a sufficient height to maintain the oil level above the lower ends of the chains. This avoids use of a stuffing-box.

As there will be considerable wear on the chains, so that they will tend to lengthen themselves, I provide means for adjusting the upper sprocket wheels 45 that carry the upper ends of the chains. The preferred construction for this purpose is illustrated in Fig. 6 which should be referred to in connection with Fig. 1. Each sprocket wheel 45 has its shaft 46 mounted in a bearing 47 carried on a bearing block 48. This bearing block is constructed so that it can be clamped rigidly to the frame 1 at any desired height. For this purpose I prefer to provide the

frame with a pair of racks 49 corresponding to each bearing block 48, and each bearing block is provided with a cap 50 having rack teeth 51 to engage with the teeth of the racks 49. The teeth on the racks 49 preferably have upwardly and outwardly inclined faces which permit the cap 50 to ride over the same in an upward direction when the bearing blocks are being adjusted upwardly. The cap bolts 52 are secured in place by clamping bolts 52. Any suitable means may be provided for adjusting the bearing blocks 48 upwardly when the clamping bolts 52 have been loosened. However, I prefer to accomplish this by providing suspending hanger bars 53 (see Fig. 1), the upper ends of which are threaded and pass through horizontal flanges in a cross-bar 54 of the frame. The threaded ends of these hanger bars carry adjusting nuts 55 that can be tightened up to pull the blocks 48 upwardly. The lower ends of these hanger bars 53 have eyes such as the eye 56 illustrated in Fig. 2a. These eyes are formed at lower ends of the hanger bars will enable them to be attached to the blocks by bolts 57.

It may be necessary from time to time to remove the cross head 4 for repairing the same, and in order to accomplish this I provide the cross head guide 5 with a removable section 58 (see Fig. 1), the ends of which are maintained in alignment with angle irons that form this guide by means of clips such as the clip 59 secured in place by removable bolts.

As the total weight of the apparatus is not very great, even including the frame, it can be supported directly on the derrick floor 60. In order to give access to the upper end of the frame 1, it may be provided with a small ladder 61 at one side and also be constructed with a crow's nest 61 near the level of the sheaves 26 and in a position from which the adjusting nuts 55 can be reached whenever it is necessary to adjust the upper sprockets.

The shafts of the lower sprocket wheels 38 are supported on inboard bearings 62 (see Fig. 8) which are in the form of blocks and carried in the lower ends of channel bars 63 that are attached at their upper ends to cross bars 64 of the frame 1.

In order to enable the inertia of the counterweights to be overcome at the end of the down stroke, I provide the apparatus with means for attaining the effect of a flywheel. For this purpose I prefer to provide a flywheel 66 on each end of the shaft 35 (see Fig. 7).

In practice, the blocks 14 should have a depth of about three-quarters of the diameter of the sprocket wheels. This seems to facilitate their ease of travel in the cross-head slot 8. It is also desirable in practice to line the faces of the slot 8 with hardened steel wear strips 8a such as illustrated in Fig. 5.

At the bottom of the down stroke, the cross-head 4 dips in the oil bath. In practice, brushes (not illustrated) dip in the bath and wipe the guide 6 with lubricant. As the cross-head dips in the bath the sleeve 44 of the bath passes through a clearance opening 44a in the bottom of the cross-head. This is practicable because at this moment the blocks 14 are at the outer ends of the cross-head. In practice, the brushes should be located at the ends of the cross-head to dip in the lubricant and apply it to the guide-ways 6 on the up-stroke.

If desired, this apparatus can be used for pulling the pump-rod. In doing this, it would be

necessary to stop the stroke at the top, support the rod in a slip-collar, loosen the clamp 8, and then drive the cross-head down and take a new grip on the rod. By arranging for greater clearance, tubing could be pulled in the same way.

If desired, dash pots of suitable construction may be employed to cooperate with the counterweights to cushion the movement of the rod at both ends of the stroke.

I claim:

1. In a long-stroke deep well pump, the combination of a frame, a flow-pipe in the well, a pump-rod extending down into the flow-pipe, a cross-head, a driving connection between the pump-rod and the cross-head, means for guiding the cross-head to reciprocate on the frame, four endless drive chains disposed in pairs with one drive chain of each pair located on one side of the plane of movement of the cross-head, and the other chain of that pair located on the other side of the plane of movement of the cross-head, a pair of driving-members for the cross-head corresponding to each of said pairs of driving chains and supported by the opposite runs of the said chains, a pair of oppositely disposed counterweights disposed one on each side of the axis of the pump-rod and guided to move in a substantially vertical direction on said frame, the weight of the counterweights being proportioned with respect to the weight of the pump-rod and fluid pumped, whereby the difference in weight between the counterweights and the weight of the fluid pumped plus the weight of the rod string on the upstroke, is substantially equal to the difference between the weight of the counterweights and the weight of the rod string on the downstroke of the latter to insure the maintenance of a constant load on the chains in the same direction throughout the reciprocatory movement of the pump-rod.

2. In a long-stroke deep well pump, the combination of a frame, a cross-head, means for guiding the same to reciprocate on the frame, a pump-rod, means for connecting the pump-rod to the cross-head, four endless chains disposed in pairs with one chain of each pair located on one side of the plane of movement of the cross-head and the other chain of that pair located on the other side of the plane of movement of the cross-head, a pair of driving members for driving the cross-head, connected to opposite runs of the said chains, means for driving said chains, and a pair of oppositely disposed counterweights disposed one on each side of the axis of the pump-rod, the weight of the counterweights being proportioned with respect to the weight of the pump-rod and fluid pumped, whereby the difference in weight between the counterweights and the weight of the fluid pumped plus the weight of the rod string on the upstroke, is substantially equal to the difference between the weight of the counterweights and the weight of the rod string on the downstroke of the latter to insure the maintenance of a constant load on the chains in the same direction throughout the reciprocatory movement of the pump-rod, and a fly-wheel associated with the chains to supply energy for assisting in reversing the direction of movement of the counterweights at the end of their down stroke.

3. In a long-stroke deep well pump, the combination of a frame, a cross-head, a pump rod, means for connecting the cross-head to the pump rod to reciprocate the latter, driving means in-

cluding endless chains disposed on opposite sides of the plane of movement of the cross-head, a flow pipe in which the pump rod reciprocates, counterweights connected to said cross-head, the weight of the counterweights being proportioned with respect to the weight of the pump-rod and fluid pumped, whereby the difference in weight between the counterweights and the weight of the fluid pumped plus the weight of the rod string on the upstroke, is substantially equal to the difference between the weight of the counterweights, and the weight of the rod string on the down-stroke of the latter to insure the maintenance of a constant load on the chains in the same direction throughout the reciprocatory movement of the pump-rod.

4. In a deep well pump, the combination of a pair of drive chains, a pump rod having a driving cross-head between said chains, said cross-head having a transverse guide-way, a driving member, chains having special links, means connecting said driving member to said special links including a swivel connection permitting relative movement of the two special links on a transverse axis between the chains and thereby enabling the chains to adapt themselves to any irregularities of faulty alignment in the chain supports or sprocket wheels for the same.

5. In a deep well pump, the combination of a pair of drive chains, a pump rod having a driving cross-head between said chains, said cross-head having a transverse guide-way, a driving member, chains having special links, means connecting said driving member to said special links including a swivel connection, said swivel connection including a pin secured to one of the links and a sleeve receiving the pin and secured to the opposite link, said pin and sleeve cooperating to permit relative movement of the two special links on a transverse axis between the chains and thereby enabling the chains to adapt themselves to any irregularities or faulty alignment in the chain supports or sprocket wheels for the same.

6. In a deep well pump, the combination of a pair of drive chains, a pump rod having a driving cross-head between said chains, said cross-head having a transverse guide-way, a driving member, chains having special links, means connecting said driving member to said special links including a swivel connection, said swivel connection including a pin secured to one of the links and a sleeve receiving the pin and secured to the opposite link, said pin and sleeve cooperating to permit relative movement of the two special links on a transverse axis between the chains and thereby enabling the chains to adapt themselves to any irregularities or faulty alignment in the chain supports or sprocket wheels for the same, and means connecting the pin and the

60 sleeve operating to permit a limited relative longitudinal movement of the pin and the sleeve.

7. In a pump jack for reciprocating a pump-actuating member, an endless chain comprising 5 a plurality of links, a pair of sprockets for the support of said chain, means to move said chain over said sprockets, means to transmit the motion, in two opposite directions, of one of said links during movement of said chain to said 10 pump-actuating member, said last-named means including a lost-motion connection between said chain and said pump-actuating member to dissipate the motion of said link in a direction transverse to the motion transmitted to said 15 pump-actuating member, and means to counter-balance a portion of the weight suspended from the cross head on the upstroke of the latter, the weight of said counterbalancing means being in excess of the weight suspended from the cross head on the down-stroke of the latter, said excess being, in terms of pounds, substantially equal to the uncounter-balanced portion of the weight suspended from the cross head on the upstroke of the latter.

20 8. In a well pump having a plunger, a cross head and means to connect said cross head to the pump plunger, a chain including a special link, means to support said chain with opposite reaches extending vertically, means to drive said 25 chain in one direction to move said link successively through said vertical reaches in opposite directions, means to connect said link to said cross head to reciprocate the latter, a counterweight connected to said cross head to oppose 30 the weight of said first-named means and the fluid in the well being pumped during the up-stroke of the cross head, the difference between the weight of the fluid column pumped plus the weight of said first-named means on the up-stroke and the weight of the counterweight being substantially the same as the difference between the weight of the counterweight and said first-named means on the downstroke.

35 9. In a pump jack, a pair of vertically aligned sprockets, an endless chain carried by said sprockets with opposite reaches of the chain extending vertically, a string of sucker rods connected to said pump, said chain including an anchor link, connecting means to connect said 40 link of said chain to the sucker rod string, drive means for one of said sprockets to move said link alternately through opposite vertical reaches of said chain, and a counterweight attached to said 45 afore-mentioned connecting means to oppose the weight of the sucker rod string and of the fluid in the well being pumped to substantially equalize the tension on said chain through a complete 50 cycle of the pump.

LUTHER A. BLACKBURN.
